UNITED STATES PATENT OFFICE.

KRYN VAN SETRES, OF PATERSON, NEW JERSEY.

BILLIARD-CUE BRIDGE.

SPECIFICATION forming part of Letters Patent No. 774,621, dated November 8, 1904.

Application filed October 21, 1903. Serial No. 177,960. (No model.)

To all whom it may concern:

Be it known that I, KRYN VAN SETRES, residing in Paterson, Passaic county, and State of New Jersey, have invented certain new and 5 useful Improvements in Billiard-Cue Bridges, of which the following is a specification.

This invention relates to bridges or guides for employment in controlling the movement of a billiard-cue in executing a shot; and the 10 more prominent object of the invention is the provision of a simple, light, and comparatively inexpensive device for the purpose stated which can be affixed to and conveniently retained upon the index-finger of the 15 hand of the player, which is passive during the operation of shooting, the said device being of such character that it will in no way encumber or objectionably interfere with the customary movements of the hand of the 20 player during the game.

With the above and other purposes in view the novel device consists of a peculiar construction involving a ring of such diameter and spring character that the same may be 25 readily slipped and retained upon the index-finger of one hand, said ring being provided with an upper pair of relatively separated and outwardly-curved members constituting guides and rests for the cue, so as to steady 30 the same and permit the shot to be accurately executed.

There are other important features connected with the invention which, besides those alluded to, are clearly set forth in the subsequent detailed description.

In the accompanying drawings, forming part of this specification, Figure 1 is a view illustrating a hand in a familiar position occupied in executing a shot, my improved 40 guide or bridge being represented on the index-finger and the cue relation being indicated in dotted lines. Fig. 2 is a view of a hand on a somewhat larger scale and representing the same in another position, the novel 45 bridge or guide and the cue relation therewith being also indicated in this figure. Fig. 3 is an enlarged elevational view of said device. Fig. 4 is a plan view of the same. Fig. 5 is a side view showing a modified form of 50 the device. Fig. 6 is a part-sectional view

showing a form of the device wherein the guide members are equipped with antifriction provision.

In the form of the invention illustrated in Figs. 1 to 4, inclusive, the device is represented as consisting of a single piece of wire of the proper gage and of more or less resilient character to afford the desired amount of spring. This piece of wire is bent to present a circular body A, which will normally be of such 55 diameter that, in connection with its spring quality, it can readily be expanded to a limited extent in slipping it upon the index-finger of one hand, so that it will tend to contract, and thus be retained in position upon said 60 finger. The formation of the circular body A is such that terminal portions of the wire contiguously extend beyond the same at one point, as indicated most clearly in Fig. 3, and these portions are bent first with a slightly- 65 inward curvature, as shown at a, and then outwardly diverged with a moderate curvature, as indicated at a', thus presenting two 70 coactive members A' of the configuration indicated in the last-mentioned figure of the 75 drawings. It will be observed by reference more particularly to Fig. 4 that the circular body A is composed of two circular convolutions a² a³, which are connected at the top by the lateral diagonally-disposed portion a', the 80 members A' being located at opposite sides, 85 respectively, of said portion.

It will be readily comprehended from the foregoing description that with the device adjusted upon the index-finger of what may be referred to as the "passive hand" of the player and with the curved members A' of the device uppermost said device may be utilized as a bridge or guide for accurately directing the cue movement, this latter being 90 accomplished by causing the cue to rest in the upper flared portion of the members, the comparative limited character of the contact between such members and cue obviating any serious retardation or resistance to the cue 95 movements. The peculiar character and disposition of the diagonal portion a' are such that said portion imparts considerable strength to the device while yet permitting the location of the members A', so that they will be 100

in proper mutual relation for supporting the cue.

As before stated, the device is not only highly useful in playing billiards, but it is extremely simple and can be produced in large quantities at comparatively slight expense. Its general configuration is such that when being utilized it will not seriously present objectionable projecting parts or otherwise tend to obstruction or inconvenience. The general size and form of the device permit of its being conveniently carried in the vest or any other pocket desired.

The essential principles of the novel cue-guide can be embodied in numerous forms other than those I have so far described. For instance, as illustrated in Fig. 5, said device may be produced from a length of tape-spring sufficiently narrow as to not be cumbersome.

20 In this arrangement an inner ring-body A² can be formed and the spring so arranged at the base thereof as to permit portions A³ to embrace said body at each side and at their upper terminals to be curved for presenting the 25 guide members A³. It will be observed that the upper part A⁶ of the ring-body constitutes the closed portion between the members A³.

It will be convenient to equip the upper guide members with revoluble antifriction 30 provision. One arrangement for accomplishing this is set forth in Fig. 6, wherein the upper members A⁸ have approximately spherical rollers A¹⁰ revolubly mounted therein and retained in position between the lower and upper 35 per bends A¹¹ A¹² of the members. These rollers may be of glass, porcelain, ebony, or other suitable hard material. It will be observed that the opposite surfaces of these rollers conjointly present a cue-rest partaking generally 40 of the configuration involved in the guide members of the previous forms.

I do not wish to be understood as limiting myself to any of the particular configurations and arrangements of the device shown and described, but reserve the right to all modifications that may be fairly within the scope of my invention.

Having now described my invention, what I claim as new, and desire to secure by Letters 45 Patent, is—

50 1. A billiard-cue bridge or guide comprising a single length of narrow resilient metal presenting a ring-body closed at the bottom and sides and providing at its top a horizontal portion beyond and above which the ter-

minals relatively diverge to form upper guide members.

2. A billiard-cue bridge or guide comprising a single length of narrow resilient metal presenting a ring-body closed at the bottom and sides and presenting at its top a horizontal portion beyond and above which the terminals relatively diverge to form upper guide members, the parts at the top of the ring-body being disconnected to permit the expansion of the latter to accommodate different-sized fingers.

3. The within-described billiard-cue guide, comprising a single piece of wire presenting two ring convolutions connected at their top 70 by a laterally-disposed diagonal portion A⁴, the terminals of the wire presenting upper oppositely-diverging guide members located on opposite sides of said diagonal portion.

4. A billiard-cue bridge or guide comprising a single length of narrow resilient metal presenting a ring-body closed at the bottom and sides and providing at its top a horizontal portion beyond and above which the terminals are spread to form relatively diverging 80 members, said members having upper and lower bends, and rollers revoluble on said members between the upper and lower bends thereof.

5. A billiard-cue bridge or guide comprising a plurality of convolutions formed of a single length of narrow resilient metal presenting a ring-body closed at the bottom and sides, said ring forming an offset at the top, whereby the terminals of the ring are oppositely disposed at the sides of said offset portion and said terminals projecting above the body of the ring and relatively diverging to form guide members; substantially as shown 90 and described.

6. A billiard-cue bridge or guide formed of a plurality of convolutions presenting a ring-body closed at the top and sides, the terminals of the said strip of metal projecting above the said ring-body and relatively diverging 100 to form guide members; substantially as described.

In testimony whereof I have signed my name to this specification in the presence of two subscribing witnesses.

KRYN VAN SETRES.
